UNITED STATES PATENT OFFICE.

JOHN CALVIN BEEKMAN, OF TARPON SPRINGS, FLORIDA.

RAILROAD-SPIKE.

SPECIFICATION forming part of Letters Patent No. 592,222, dated October 19, 1897.

Application filed November 6, 1896. Serial No. 611,272. (No model.)

To all whom it may concern:

Be it known that I, JOHN CALVIN BEEKMAN, a citizen of the United States, residing at Tarpon Springs, in the county of Hillsborough and State of Florida, have invented certain new and useful Improvements in Railroad-Spikes, of which the following is a full and complete specification, such as will enable those skilled in the art to which it appertains to make and use the same.

This invention relates to railway and similar spikes; and the object thereof is to provide an improved spike of this class which is so constructed that when driven into a railway-tie or other article it will be locked therein.

The invention is fully disclosed in the following specification, of which the accompanying drawings form a part, in which like letters of reference designate the same parts wherever found throughout both views, and in which—

Figure 1 is a perspective view of my improved spike, and Fig. 2 a longitudinal section on the line 2 2.

In the practice of my invention I provide a spike A, which is provided with a head B, of the usual form, one side of which projects as shown at C, and is adapted to overlap the base-flange of a railway-rail.

The body portion of the spike A is provided with an oblong slot D, which is open at its lower end, and by means of which the said spike is divided into two similar halves or parts E, and at the upper end of the slot D is a downwardly-directed wedge-shaped projection G, and the lower ends of the separate parts or halves E of the spike are beveled or inclined on their inner surfaces, as shown at H, so as to form cutting edges K, and the outer sides thereof are cut away, as shown at M, and the operation will be readily understood from the foregoing description, when taken in connection with the accompanying drawings and the following statement thereof.

When the spike is driven into a railway-tie, the lower ends of the separate parts or

sides E thereof are curved outwardly and form hooks by means of which the spike will be securely held in the tie, and the downwardly-directed wedge-shaped projection G, at the upper end of the slot D, is designed to enable the solid upper portion of the spike to penetrate the tie, as will be readily understood.

The cut-away portions M on the outer sides or surfaces of the lower ends of the separate parts or sides E of the spike are not essential, but I prefer to form the ends of the separate sides E of the spike in this manner in order to enable the cutting edges K to more easily penetrate the wood of the tie.

My improved spike is simple in construction and operation, and is well adapted to accomplish the result for which it is intended.

Having fully described my invention, I claim as new and desire to secure by Letters Patent—

1. In a railway-spike, an ordinary head, a body portion in combination therewith and provided with an oblong slot therein opened at the lower end, a downwardly-directed wedge-shaped projection provided with a cutting edge at the upper end of said slot and the lower end of the legs being beveled, substantially as described.

2. The herein-described railway-spike comprising a body portion A, a slot D, dividing the lower part into two parts E, thereby forming spikes, a wedge-shaped projection G, provided with a cutting edge the lower ends of said spikes being beveled on the inner side thereof as shown at H thereby forming cutting edges K, and the outer sides thereof being cut away as shown at M, substantially as and for the purpose set forth.

In testimony that I claim the foregoing as my invention I have signed my name, in presence of the subscribing witnesses, this 23d day of October, 1896.

JOHN CALVIN BEEKMAN.
